CLAIM

The ornamental design for a surveillance camera, as shown
and described.

DESCRIPTION

FIG. 1 is a front perspective view of a surveillance camera
showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings depict portions of
the surveillance camera that form no part of the claimed
design.**1 Claim, 5 Drawing Sheets**(56)
